UNITED STATES PATENT OFFICE.

WALTER CHAPMAN WOOLWINE, OF NASHVILLE, TENNESSEE.

DESIGN FOR WRAPPING-PAPER.

SPECIFICATION forming part of Design No. 23,948, dated January 8, 1895.

Application filed November 5, 1894. Serial No. 527,975. Term of patent 7 years.

To all whom it may concern:

Be it known that I, WALTER CHAPMAN WOOLWINE, a citizen of the United States, residing at Nashville, in the county of Davidson and State of Tennessee, have invented and produced a new and original Design for Wrapping-Paper; and I do hereby declare the following to be a full, clear, and exact description of the same, reference being had to the accompanying drawing, forming a part thereof.

The drawing represents a top plan view of a sheet of wrapping paper having upon it the representation of a watermelon surrounded by a number of other watermelons, embodying my new design.

The leading feature of my design consists of a sheet of wrapping paper having upon it the representation of a watermelon surrounded by a number of other watermelons.

A in the drawing represents a sheet of wrapping paper, on which is printed the representation of a large watermelon B having the usual mottled surface and with a slice cut

therefrom so as to expose the meat and seeds of the fruit in the interior b. On one end of the water melon is represented a small stem c indicating a portion of the vine from which the fruit was plucked. Other representations of watermelons C similar to melon B except that they are much smaller are printed in gradually widening circles about the central melon B but in different positions, some vertical, some horizontal and some inclined so as to present to the eye an irregular arrangement of watermelons each with a slice cut therefrom and surrounding a larger and centrally arranged melon.

What I claim is—

The design for wrapping paper substantially as shown and described.

In testimony whereof I hereunto affix my signature in presence of two witnesses.

WALTER CHAPMAN WOOLWINE.
